A. J. LOEPSINGER

FIRE EXTINGUISHER SPRINKLER SYSTEM

Filed April 6, 1926

Patented June 26, 1928.

1,675,184

UNITED STATES PATENT OFFICE.

ALBERT JOHN LOEPSINGER, OF PROVIDENCE, RHODE ISLAND, ASSIGNOR TO GENERAL FIRE EXTINGUISHER COMPANY, A CORPORATION OF DELAWARE.

FIRE-EXTINGUISHER SPRINKLER SYSTEM.

Application filed April 6, 1926. Serial No. 100,023.

Heretofore, in fire extinguisher systems for buildings, it has been customary to provide piping leading from a source of water supply and extending to various portions of the building by means of branch pipes and feed lines, the latter suspended from the ceilings and provided at intervals along their length with automatic sprinklers which, under the action of heat, cause the systems to operate to supply water under pressure to the feed lines and ultimately be released through the sprinklers in the form of spray for the purpose of extinguishing the fire, the sprinklers being attached to lateral outlets of reducing T fittings which are also the means of uniting adjacent pipe sections of different diameters constituting the feed lines aforesaid.

My invention has for its object the construction and installation of water distributing piping for supplying sprinklers in a fire sprinkler system, whereby the mechanical installation is greatly simplified in respect to the number of parts and joints required, the supply of the water to the sprinklers is more uniformly distributed, the available effective pressure at the sprinklers is increased with a given initial pressure in the supply main, and the weight of the piping carrying the sprinklers is considerably reduced.

With the above and other objects in view, the nature of which will be more fully understood from the description herinafter, the invention consists in the novel construction of fire extinguisher sprinkler system, as hereinafter more fully described and defined in the claims.

Referring to the drawings: Fig. 1 is a plan view illustrating a portion of a fire extinguisher sprinkler system embodying my invention; Fig. 2 is a vertical section along one of the sprinkler supporting and water supplying feed mains; Fig. 3 is a plan view of a modified closure for the terminal pipe of one of the branch mains shown in Fig. 2; Fig. 4 is a modification of the piping shown in Fig. 2, and more particularly in respect to the upsetting of the metal at the pipe end to thicken it; Fig. 5 is a sectional view illustrating the special manner of forming the threaded union between adjacent pipe ends; Fig. 6 is a plan view of one of the pipe lines, modified as to the place of attachment of the sprinklers;

and Fig. 7 is a vertical section showing the manner of heretofore forming the connection of the pipes and sprinklers by use of cast metal fittings.

The general piping installation employed for fire extinguisher sprinkler systems consists of risers of large size leading from a source of water supply, horizontal cross mains receiving their water supply from the risers, and horizontal feed lines of piping which receive water from the cross mains and supply it to the sprinklers which are attached to said piping at intervals along the lengths thereof. This arrangement of piping is shown in Fig. 1, as it might apply to a small portion of a building, in which 2 is the riser, 3 the cross mains and 4 are the feed lines for the sprinklers 19.

As my invention is more particularly directed to the feed lines 4 and their special construction, I have shown the same in detail in Figs. 2, 3 and 4. In Fig. 2, I have only indicated three pipe sections of different diameters, by way of example, though there may be five such sections as shown in Fig. 1, or any other number, as the installation may require. The numbers and lengths of these feed lines 4 may be varied according to the requirements of the building and may ramify through it and be proportioned as to the diminishing diameters of their pipe sections, in accordance with the number and position of the sprinklers to be supplied. In respect to the particular example shown in Fig. 1, the cross mains 3 may be of two and one-half inch diameter, and the pipe sections 5, 6, 7, 8 and 9 of the branch feed lines may respectively have diameters of two inches, one and one-half inches, one and one-quarter inches, one inch, and three-quarter inch, diminishing as they are arranged further from the cross main 3. Except for the difference in their diameters, the pipe sections 5, 6, 7, 8 and 9 may be alike, that is to say, one end 11 may be straight of full diameter and externally screw threaded as usual in piping, but the other end 10 is reduced in diameter slightly and internally screw threaded, so that the end 11 of one pipe section makes a screw joint with the internal threaded end 10 of the next pipe section, as at 12. It will thus be seen that the pipe sections 5, 6, 7, 8 and 9 are directly screwed together in series and without any pipe fittings or couplings.

as heretofore required and as shown in Fig. 7 by way of illustration.

As the internal diameters of adjacent pipes, such as 8 and 9, differ only slightly more than the thickness of the metal of the smaller of the pipes, it will be seen that the contraction of the end 10 provides only a small curved enlargement as at 13 and no material pocket or obstruction to the flow 10 of the water. Practice has shown that the compression of the pipe end to reduce its diameter at 10 provides some increased metal and that the screw joint formed is strong and durable. Where light weight 15 piping is employed or where greater strength at the joint is required, the pipe end may be upset longitudinally at the same time the diameter is being reduced, as indicated at 10^a in Fig. 4. Furthermore, as the 20 joint 12 is required to be both air and water tight, it is desirable to cut the internal thread on the end 10 of one pipe section at a slightly greater angle than that given to the thread cut on the end 11 of the adjacent 25 pipe sections, as indicated in Fig. 5, so that the external threads on the end 11 first engage the internal threads at a distance from the end of the part 10 to produce a tight joint; and it will be understood that a very 30 tight joint may be made in this way, since a great deal more force may be exerted in completing the joint without stretching the pipe end 10 than would be the case if the stretching action first came upon the 35 extremity of the end part 10.

As shown, the pipe sections 5, 6, 7 and 8 are each laterally bored through at 16 near their ends 10 farthest removed from the cross pipes 3; and about these holes are respectively arranged steel nozzles 15 which are electrically or otherwise welded to the pipe sections at 17 and are internally screw threaded as at 18. The sprinklers 19 may be of any suitable construction and provided with screw threaded inlet nipples 20 which screw into the threaded portions 18 of the nozzles 15. In Fig. 2, I have only shown one sprinkler 19, but it is to be understood that a sprinkler is fitted to each nozzle 45 15. Pipe section 9 may be a straight length of tube with its terminal end closed by a cap 14 and with a threaded nozzle 15 welded to the pipe section, as in the case of the sections 5, 6, 7 and 8, before referred to. If 50 desired, this section 9 may be reduced at 10 as in the other pipe sections and sealed with a plug 14^a as shown in Fig. 3, but the special advantages of the other joints not being available at the terminal end of section 9, 55 I do not restrict myself as to the means of sealing the end of said pipe.

By comparing the construction of my improved piping with Fig. 7 showing the construction heretofore employed, it will be seen 60 that the latter requires reducing T's 23

into one opening of which the straight length of larger pipe 21 is screwed and into the other opening of which the straight length of the smaller pipe 22 is screwed, thus requiring two screwed joints. The 70 third opening in the T receives the threaded nipple 20 of the sprinkler 19. The T 23 provides a hollow chamber 24 which sets up objectionable eddy currents and increases the flow of water to the nozzles. It will 75 also be understood that as the fittings 23 vary very considerably in size according to the different internal diameters of the pipe sections, it is evident that the hollow chambers 24 which produce the eddy currents 80 very materially vary and consequently there is a lack of uniformity in the distribution of the water from the sprinklers and a shortage of water to the distant nozzles 85 when the piping extends to a great distance, as in large buildings.

Some of the special advantages of my improved piping may be enumerated as follows: One threaded joint is eliminated in forming the union of two consecutive lengths of pipe, in that the pipe sections are united directly without the intervention of fittings; trouble due to breakage and leakage on account of porous castings, such as the fittings heretofore required, are avoided; 90 lightness of construction is assured in that the heavy castings constituting fittings, such as reducing T's, are entirely eliminated; eddy currents in the water flow are largely eliminated and consequently the supply of water to the sprinklers is more uniform and constant and reaches to greater distances with adequate flow assured when the system is in operation; the sprinklers may be located along the length of piping wherever 95 found desirable; there is less weight to the piping than heretofore required, and consequently less strain upon the ceiling structures of the building; and there is considerably less friction loss in the feed lines so 100 that a greater proportion of the pressure at the supply or entrance to the feed lines is available to force the water from the 105 sprinklers when opened. It will be understood that while there is, to a small extent, 110 eddy currents produced adjacent to the reductions in internal diameters of the joined pipe sections, the effect of said eddy currents (in increasing the flow from the nozzles) may be still further minimized, if desired, by providing nozzles on the piping 115 adjacent to the end 11, as indicated at 15^a in Fig. 6, since at those portions of the pipes there are no obstructions or interference with free flow of water.

It will be understood that the sections of piping which constitute the feed lines 4 need not vary greatly in length and may, therefore, be made up on shop orders and carried in stock. The simplicity of con- 120 125 130

struction would not only enable the cost to be reduced in the manufacture of the parts required, but the labor in installing my improved system is also considerably below the 5 cost of installation employing the reducing T fittings as heretofore required. Furthermore, if the pipe sections are made long for special work, a plurality of nozzles 15 and 15^a may be formed on each section, if so 10 desired.

It will now be apparent that I have devised a novel and useful construction which embodies the features of advantage enumerated as desirable, and while I have in 15 the present instance shown and described the preferred embodiment thereof which has been found in practice to give satisfactory and reliable results, it is to be understood that I do not restrict myself to the details, 20 as the same are susceptible of modification in various particulars without departing from the spirit or scope of the invention.

Having thus described my invention, what I claim and desire to secure by Letters Patent is:

1. A pipe section for a distributing feed line for sprinklers in a fire extinguisher sprinkler system, consisting of a straight pipe of circular cross section having one end 30 of the full diameter and screw threaded externally and having the other end reduced in diameter and internally screw threaded whereby it may receive the screw threaded end of a similar pipe section of the next 35 commercial lesser diameter, and wherein further, the cylindrical body portion of the pipe has a lateral aperture intermediate of its

ends and an internally screw threaded nozzle secured to the body about the aperture.

2. The invention according to claim 1, 40 wherein further, the aperture and nozzle are arranged a short distance from the reduced and internally screw threaded end of the pipe and the nozzle is secured to the outside of the body by being welded thereto. 45

3. In a fire extinguisher sprinkler system, a plurality of distributing pipe lines receiving water from a common source and adapted to supply water to a plurality of sprinkler nozzles arranged along their length, 50 said pipe lines each comprising a plurality of pipe sections of standard sizes and successively decreasing in internal diameters and directly connected end to end by single screw joints, said pipe sections each comprising a tubular pipe length having one end of the full diameter of the pipe and externally screw threaded and the other end reduced in diameter and internally screw threaded to receive the external screw 60 threaded end of the next smaller pipe section, each pipe section further provided with a lateral aperture at a distance from the ends, combined with sprinklers attached to said lateral apertures of the pipe sections. 65

4. The invention according to claim 3, wherein further, the lateral openings in the pipe sections are formed with screw threaded nozzles welded to the outer walls of the pipe sections near their contracted and internally screw threaded ends. 70

In testimony of which invention, I hereunto set my hand.

ALBERT JOHN LOEPSINGER.
